UNITED STATES PATENT OFFICE.

CHARLES PARTINGTON, OF NEWPORT, KENTUCKY, ASSIGNOR TO THE
WEIR FROG COMPANY, OF CINCINNATI, OHIO, A CORPORATION.

SWITCH-BAR ATTACHMENT.

SPECIFICATION forming part of Letters Patent No. 739,441, dated September 22, 1903.

Application filed June 26, 1903. Serial No. 163,166. (No model.)

To all whom it may concern:

Be it known that I, CHARLES PARTINGTON, a citizen of the United States, residing at Newport, in the county of Campbell and State of Kentucky, have invented certain new and useful Improvements in Switch-Bar Attachments, of which the following is a specification.

The object of my invention is to provide a strong and more durable bracket for supporting a tie-bar and connecting it to the switch-rail, all of which will be fully set forth in the description of the accompanying drawings, forming a part of this specification, in which—

15 Figure 1 is a plan view of a blank. Fig. 2 is a side elevation of the bracket in position for use. Fig. 3 is a front elevation of the bracket. Fig. 4 is a perspective view of the inner face of the bracket.

20 1 represents a main rail; 2, a switch-rail; 3, a tie-bar or a switch-bar; 4, the bracket for rigidly connecting the tie-bar to the switch-rail; 6, the bolts for fastening the brackets to the switch-rail; 7, a bolt for connecting the tie-bar to the bracket.

25 The bracket is formed from a blank shown in Fig. 1 into the form shown in Figs. 3 and 4. It is provided with a flange *a*, a neck *b*, and a hollow shank *c*.

30 *d* represents the orifice pierced in the back of the shank through which the tie-bar is inserted.

e represents a recess formed in the neck of the flange which abuts against the outer edge 35 of the switch-rail flange.

g represents curved oval-shaped flanges curving from the recess *e* backward and downward to the end of the shank *c*, forming a strong support or brace for the shank and 40 enabling it to withstand the strains and thrusts imparted to the switch-rail through the bracket.

By making the bracket from a rectangular blank and forming the curved flanges *g* as a 45 continuous connection of the shank to the body of the brace the same amount of metal is employed in all sections of the brace, and the curved form of the flanges *g* strengthen

the bracket at the point where the greatest strain occurs—namely, between the bolt and the neck of the recess engaging the edge of the rail-flange. I have found by experience that these brackets are strong and durable. I preferably form a recess *h* in that part of a bracket opposite the rail-flange which forms 55 a ridge *k* on the top of the bracket above the rail.

1 represents side flanges which abut firmly upon the top base of the rail-flange and forms a seat for the bracket upon the rail. This 60 method of construction enables me to use all the metal, from a rectangular blank and so dispose of it in the swaging up of the bracket as to strengthen and support the bent portions thereof.

Having described my invention, what I claim is—

1. A tie-bracket for a switch-rail, formed of a blank having four parallel sides, and forming a hollow shank at the base, and connected 70 to the rail-abutting portion of the bracket by continuous curved flanges, substantially as specified.

2. A tie-bracket for a switch-rail, formed from a rectangular blank and having angular 75 flanges to fit and abut the web and flanges of a rail, and a depending portion forming a hollow shank with continuously-curved flanges extending from the shank to the seat-flanges of the bracket, substantially as specified. 80

3. A tie-bracket for a switch-rail, formed from a rectangular blank, having vertical and inclined flanges, adapted to fit and seat upon the switch-rail, a recess formed in the neck of the flange adapted to abut the edge of the 85 rail-flange, a vertical hollow shank pierced to receive the tie-bar and continuous curved flanges formed on each side of the shank, substantially as specified.

In testimony whereof I have hereunto set 90 my hand.

CHARLES PARTINGTON.
